UNITED STATES PATENT OFFICE.

GEORGE W. STUYVERSON, OF McEWEN, TENNESSEE.

DOOR-HANGER.

No. 926,778.

Specification of Letters Patent.

Patented July 6, 1909.

Application filed March 2, 1909. Serial No. 480,837.

To all whom it may concern:

Be it known that I, GEORGE W. STUYVERSON, a citizen of the United States, residing at McEwen, in the county of Humphreys and State of Tennessee, have invented certain new and useful Improvements in Door-Hangers; and I do hereby declare the following to be a full, clear, and exact description of the invention, such as will enable others skilled in the art to which it appertains to make and use the same.

My invention relates to new and useful improvements in door hangers and more particularly to that class adapted to be used in connection with car doors and my object is to provide means for suspending the door from a track-way placed on the side of the car and a further object is to provide means for preventing the hangers supporting the door from leaving the track-way as the door is being moved back and forth.

Other objects and advantages will be hereinafter referred to and more particularly pointed out in the claim.

In the accompanying drawings forming part of this application, Figure 1 is a side elevation of a portion of a box car showing my improved device attached thereto. Fig. 2 is a top plan view of the door hanger and track-way therefor. Fig. 3 is an enlarged detail view partly in section of one of the hangers and parts to which the same is attached. Fig. 4 is a sectional view as seen on line 4—4, Fig. 3. Fig. 5 is a transverse sectional view through the track-way and supporting means therefor, and, Fig. 6 is a perspective view of one of the hangers removed from the door.

Referring to the drawings in which similar reference numerals designate corresponding parts throughout the several views, 1 indicates a car body which may be constructed in the usual manner and more particularly to that class adapted to be used for hauling freight, said body having an opening 2 in the sides thereof, through which the car may be filled or emptied and 3 indicates the usual form of door employed for closing said opening. These doors are preferably movably mounted so as to prevent the same from swinging outwardly and coming in contact with objects along the track-way and to this end I provide my improved form of hangers 4, the depending ends of which are bolted or otherwise secured to the door, while the upper ends thereof project above the upper edge of the door, said projecting portions of

the hangers being provided on their opposite faces with track and guide rollers 5, 6, and 7 and 8, respectively, said rollers being arranged in pairs and two pairs of rollers at each side of the hanger. The pairs of rollers are spaced apart to receive track flanges 9 and 10 of track bars 11 and 12, respectively, which track bars are placed at opposite sides of the hangers 4 and are secured together at their ends by introducing spacing blocks 13 between the bars and the blocks and bars are connected together by introducing bolts or rivets 14 through the ends of the bars and the interposed blocks. The bolts 14 are also preferably extended through the wall of the car, thereby securely anchoring the ends of the track bars, while the central portion of the track bars are supported by means of a strap 15, the ends of the strap being extended in vertical parallel planes, while the intermediate portion thereof is extended in a horizontal plane, the horizontal portion 16 resting on the upper edges of the track bars 11 and 12, while the lowermost vertical portion 17 rests against the outer face of the track bar 11 and is secured thereto by rivets 18, the uppermost vertical portion resting against and secured to a plate or bar 9 by bolts 20 which extend through the wall of the car, 85 said plate being riveted to the track bar 12 and extending above the same.

The pair of track rollers 5 are placed above the track flange 9 and the pair of guide rollers 6 below the track flange 9, while the track flange 10 extends between the track rollers 7 and guide rollers 8 on the opposite side of the hanger, the track rollers 5 and 7 supporting the door 3, while the guide rollers 6 and 8 prevent upward or twisting movement of the door, so that when pressure is directed against the door at any point, it will readily move lengthwise of the track flanges and will not buckle or swing edgewise. The length of the track bars is so regulated that the blocks will stop the movement of the hangers at the proper point and to further prevent outward swinging movement of the lower edge of the door, the usual or any preferred form of keepers 21 are positioned adjacent the lower edge of the door as shown in Fig. 1. It will thus be seen that by providing the track and guide rollers in pairs to fit on opposite sides of the flanges and placing the lower sets of rollers in position to engage the lower edge of the flanges, any edgewise swinging movement of the door will be

prevented, while the door will readily move lengthwise of the trackways.

What I claim is:

The combination with a door, hangers attached to said door and extending above the upper edge thereof, and rollers arranged in pairs on said hangers, two pairs of the rollers being on opposite sides of the hanger and spaced apart; of track bars having inwardly directed flanges extending longitudinally thereon and adapted to extend between the pairs of rollers on opposite sides of the

hanger, blocks at the ends of said track bars, bolts to secure the ends of the track bars to the blocks and anchor the same to an object 15 and a supporting strap at the longitudinal center of the track bars.

In testimony whereof I have signed my name to this specification in the presence of two subscribing witnesses.

GEORGE W. STUYVERSON.
